U.S. Appl. No. 15/296,436, entitled "Door Closer", by Danny Dean DeGott, filed Oct. 18, 2016.

(Continued)

Primary Examiner — Ian Simmons*Assistant Examiner* — Yolanda Robinson(74) *Attorney, Agent, or Firm* — Shane Cortesi(57) **CLAIM**

What is claimed is the ornamental shape of a door closer, as shown and described.

DESCRIPTION

FIG. 1 is a top isometric view of a door closer, showing my new design.

FIG. 2 is a bottom isometric view thereof.

FIG. 3 is a top plan view thereof.

FIG. 4 is a front elevation view thereof, with the rear elevation view being a mirror image thereof.

FIG. 5 is a bottom plan view thereof.

FIG. 6 is a left side elevation view thereof; and,

FIG. 7 is a right side elevation view thereof.

The broken lines shown in the Figures depict environmental subject matter only and are not part of the claimed design.

1 Claim, 5 Drawing Sheets(56)
